UNITED STATES PATENT OFFICE

WILFORD H. TEETER, OF DAYTON, OHIO, ASSIGNOR, BY MESNE ASSIGNMENTS, TO DELCO PRODUCTS CORPORATION, OF DAYTON, OHIO, A CORPORATION OF DELAWARE

CHARGE FORMING DEVICE

Application filed September 22, 1927. Serial No. 221,372.

This invention relates to charge forming devices for multi-cylinder internal combustion engines and more particularly to the type of charge forming device or carburetor comprising a plurality of primary fuel mixing chambers or primary carburetors one for each intake port of the engine and cooperating respectively with a plurality of secondary fuel mixing chambers each located adjacent an engine intake port and receiving fuel air mixture from a pipe connected with one of the primary carburetors and receiving air when required through one branch of an air manifold which supplies air to all of the secondary carburetors. The primary carburetors receive their liquid fuel from a common fuel bowl in which the level is controlled by a float valve.

One example of a carburetor to which the present invention relates is that disclosed in the copending application of F. E. Aseltine, Serial No. 83,979, filed Jan. 26, 1926. In the Aseltine carburetor the admission of air to the air manifold is controlled by a spring loaded valve. The throttling of the carburetor is effected by separate throttle valves one in each secondary carburetor located between the secondary mixing chamber and the engine intake port. The several throttle valves are controlled by a common operating member. The formation of a super-rich fuel mixture in each primary carburetor and the flow of this mixture to each secondary carburetor is effected or induced by the flow of air through the secondary carburetor and is therefore controlled by the throttle-valve therein.

The general object of this type of charge forming device is to secure a mixture of fuel and air in which the fuel is evenly distributed and to deliver equal quantities of said mixture having the same mixture ratio to each cylinder of the engine under various conditions of load and speed to which the engine may be subjected, without requiring the heating of the fuel or fuel mixture before it is delivered to the engine.

When a separate throttle is employed in each of the secondary carburetors as in the above copending application difficulty may

sometimes arise in securing equal distribution of the fuel mixture to the several engine ports, because of the difficulty in making the several throttles of exactly the same size or securing exactly the same adjustment of said throttles under all conditions of operation, particularly if said throttles become worn or warped.

It is the primary purpose of this invention to eliminate the possibility of such difficulty and to secure under all conditions of operation equal mixture distribution to the several engine ports, irrespective of wear, adjustment or warping of the parts.

Where separate throttles are employed in the secondary carburetors a part of the controlling mechanism is in the air manifold and a part of such mechanism in the main carbureting unit, constituting a more or less complicated structure, and presenting certain difficulties in manufacture and in disassembling for adjustment purposes.

It is, therefore, a further object of this invention to simplify the construction to facilitate manufacture and adjustment thereof.

The present invention accomplishes these general objects by a construction which avoids the use of a separate throttle valve in each of the separate secondary carburetors and which permits the use of the simplest form of secondary carburetor associated with each engine intake port. The present invention is embodied in a charge forming device comprising an air manifold which does not include any of the control mechanism of the carburetor, and a main carburetor unit adapted to be attached to and supported by the air manifold, said structure including chiefly a fuel bowl, the primary carburetors to which liquid fuel is distributed from the fuel bowl, and all of the valves and control mechanism associated therewith for controlling the flow of air through the air manifold and the flow of primary fuel mixture from the primary carburetors to the secondary carburetors at each engine intake port. In the disclosed form of this invention each secondary carburetor comprises a mixing chamber formed by an insert placed within each engine intake port before the air manifold is attached

to the engine cylinder head. The primary mixture is conducted from each primary carburetor to each secondary carburetor by a pipe which is formed of separable sections, one section being attached to the main carburetor unit referred to and the other being attached as an insert to each branch of the air manifold. In this way the main carburetor unit may be readily attached to or 10 detached from the air manifold, permitting the manufacture of the air manifold and the main carburetor as separate units.

In addition to securing these advantages, this invention aims to provide the proper fuel mixture for all conditions of speed and load of the engine, and particularly such mixtures as are economical and those which will aid in the rapid acceleration of the engine under different conditions.

20 Further objects and advantages of the present invention will be apparent from the following description, reference being had to the accompanying drawings, wherein a preferred form of embodiment of the present invention is clearly shown.

In the drawings:

Fig. 1 is a plan view of a charge forming device embodying the present invention;

Fig. 2 is a fragmentary sectional view on line 2—2 of Fig. 1;

Fig. 3 is an elevation thereof looking in the direction of the arrow 3 of Fig. 1;

35 Figs. 4 and 5 are sectional views on lines 4—4 and 5—5 respectively of Fig. 3;

Fig. 6 is an end view of the carburetor unit looking in the direction of the arrow 6 of Fig. 3;

Fig. 7 is a view of the unit looking in the direction of the arrow 7 of Fig. 3;

40 Figs. 8 and 9 are sectional views on the lines 8—8 and 9—9, respectively, of Fig. 1;

Figs. 10, 11, 12 and 13 are fragmentary sectional views taken chiefly on the lines 10—10, 11—11, 12—12, and 13—13, respectively, of Fig. 9;

Fig. 14 is a sectional view on line 14—14 of Fig. 7;

Fig. 15 is a sectional view on line 15—15 of Fig. 9;

50 Fig. 16 is a sectional view on line 16—16 of Fig. 6.

Fig. 17 is a detail view in vertical section of a modified form of the fuel valve shown in Fig. 10.

55 Fig. 18 is a plan view of such valve.

Fig. 19 is a vertical longitudinal section of a modified form of flow control device.

Fig. 20 is a vertical section on line 20—20 of Fig. 19.

60 Referring to the drawings, 20 designates the air manifold having an inlet at 21 (see Fig. 9), having three branch pipes 22 each communicating with a cylinder head intake port 23 of the conventional six cylinder engine, each intake port supplying fuel to a

pair of engine cylinders through cylinder valve ports 23a and 23b. In Fig. 1 the engine cylinder head is shown in three separate fragments 24 but it will be understood that it may be an integral structure. The air manifold 20 is secured to the cylinder block 24 in any suitable manner. Adjacent its intake 21 the manifold 20 is provided with a flange 25 to which may be bolted the main carburetor unit which will now be described.

70 The carburetor unit comprises the conduit and primary carburetor block 30 and 31, respectively, which are secured together by screws 32 (see Figs. 6 and 7) and which after being assembled are secured to the flange 25 by screws 33. The members 30 and 31 in turn support a housing 34 attached thereto by screws 35 (see Figs. 1, 6 and 7). The housing 34 supports above it an air inlet member 36 which is attached by screws 36a, and the 80 housing 34 supports below it a frame 37 attached to it by screws 38. The frame 37 supports the fuel bowl 39 attached thereto by screws 40. Between these various frame members sealing gaskets are placed as shown. 85

90 Fig. 2 shows a section of the passage through which the liquid fuel is admitted to the fuel bowl 39 and means for controlling the flow thereto. The frame member 37 is provided with a tubular extension 210 which receives the pipe connection 211 which is tapped at 212 to receive a pipe connected with the source of fuel supply. Fuel is required to pass through a screen 213 located in the passage 210 which is connected with a passage 214 leading to a valve seat member 215 providing a valve seat 216 and outlet holes 217. The valve seat member 215 guides a float operated valve 218 which is yieldingly urged upwardly by lever 219 carrying a float 220. The lever 219 is pivotally mounted upon a pin 221 supported by brackets 222, one of which is shown in Fig. 2 attached to the frame member 37.

95 100 105 110 115 120 125 130 The primary carburetors of the charge forming apparatus are located within the primary carburetor block 31. Each primary carburetor includes a horizontal passage 41 in the block 31 into which liquid fuel is delivered through an orifice 42 provided by a bushing 43 screwed into the block 31 the passage 41 constituting a primary mixing chamber. The flow of fuel from the orifice 42 into the primary mixing chamber 41 is induced by the depression existing at the orifice 42 due to conditions which will be described later. Air for carrying the liquid issuing from the orifice 42 into the mixing chamber 41 is admitted through a hole 44 in the housing 34 and through a bushing 45 having a bevelled lip 46 extending close to the vertical center line of the orifice 42 for the purpose of minimizing the effect upon the flow of liquid fuel due to the velocity of the air passing through the bushing 45. Each primary

mixing chamber 41 receives its liquid fuel from a distributing block 50 which is attached to the primary carburetor block 31 by the screws 32 as shown in Figs. 6 and 7. The distributor block provides a liquid fuel manifold 51 having separate branches 52 each leading to one of the metering bushings 43. The entrance 53 to the manifold 51 is in communication with a passage 54 formed in a block 55 also secured to the distributing block 50 by the screws 32. The passage 54 leads through a nipple 56 projecting downwardly from block 55 and conduit which extends below the level 59 of fuel in the fuel bowl, said conduit comprising connected pipes 57 and 58.

Under certain conditions fuel is admitted to the pipe 58 only through a metering plug 60 having an orifice 61. Fuel may be admitted to the pipe 58 also through a by-pass 62 having fuel inlet holes 63 which are shown covered by a valve 64 in Fig. 14. Under certain conditions the valve 64 will be lifted to permit fuel to flow through the hole 63 as well as through the orifice 61 to the pipe 58.

The flow of liquid fuel into the passage 54 from the pipe 57 is controlled by a metering valve 70 which is normally seated upon a seat 71 provided by the nipple 56. The valve 70 is provided with a small metering orifice 72. Under engine operating conditions producing relatively high suction at the primary nozzles 43 and consequently relatively high velocity of the flow of fuel through the passage 57, the metering valve 70 will be lifted to permit the passage of a greater amount of fuel through the passage 73 around the valve 70 to the distributing canal 51. Normally this valve remains seated to keep the mixture lean below a certain medium speed, for example 30 miles per hour, when the vehicle is running on the level.

While the fuel is flowing upwardly through the passage 54, disc check valve member 74 is lifted from its seat 75, but when the fuel ceases to flow the valve 74 will return to its seat so as to prevent emptying the distributing manifold immediately. The upward movement of the valve 74 is limited by its engagement with stop pins 76. The check valve 74 prevents the dropping of the column of liquid located above the level of the seat 75 in passage 54 down to the level of the fuel in bowl 39 when the engine speed is suddenly reduced with corresponding reduction in vacuum above the check valve. Thus the valve 74 prevents starving the engine for a period, so that the engine will operate smoothly upon a sudden reduction in speed.

The primary fuel mixture passes from each primary carburetor to one of the secondary carburetors to be described, through a separate fuel duct. Each one of these ducts includes a tube 80 inserted in the air manifold

20 so as to extend lengthwise of each one of its branches 22 as shown in Figs. 5 and 9. In the case of the center branch 22 its pipe 80 is connected directly with the outlet of the central primary mixing chamber 41 which is shown in Fig. 9. In the case of the end branches 22 of the air manifold 20, each of their pipes 80 is connected with its proper mixing chamber 41 through a separate pipe 81. Each pipe 81 has one end attached to the block 31 as shown in Fig. 1, and the other end attached to a flange 82 secured to the air manifold 20 by screws 83. It is apparent that this construction will permit removal of the unitary carburetor structure simply by removing the screws 33 and 83.

The primary fuel mixture is caused to flow out of the pipes 80 and 81 due to the difference in pressure at the outlet of such pipes and at the primary mixing chambers 41. Each secondary carburetor is essentially a plain tube carburetor in which the mixing chamber is provided by the engine cylinder head intake port 23 into which a primary mixture is delivered and is mixed with air received from an air manifold. As an aid to acceleration each engine intake port 23 may receive a bushing 85 providing a Venturi passage 86 for inducing more rapid flow of primary mixture from the pipe 80 when it is desired to accelerate the engine rapidly. The venturi 86 assists in mixing the primary mixture with air in the secondary carburetors before passing into the engine cylinders. The venturi may, however, be omitted and other flow accelerating means employed.

Owing to the fact that engine suction is effective on the secondary carburetors successively there is some interchange of air between the secondary carburetors, when the suction is high in one and low in another. Some fuel is always precipitated on the walls of the secondary mixing chambers and unless means were provided to prevent there might be some interchange of fuel as well as air between the said secondary carburetors, which would cause difficulties in distribution. To prevent such fuel interchange the branches 22 of the manifold are sloped toward the engine ports, and the branches 20 slope downwardly toward the ends of the manifold. Any fuel deposited on the walls of any secondary carburetor is prevented from flowing to any other secondary carburetor by the action of gravity.

Air for the primary and secondary carburetors is admitted through the port 90 in inlet member 36 controlled by a spring loaded valve 91 normally urged by a spring 92 against a seat 93. From the member 36 air may pass above a partition 94 in the frame 34 and thence through a passage 95 in the conduit or air throttle block 30 and into the entrance 21 of the air manifold. Each primary mixing chamber 41 is connected with the air

passage 95 by a separate passage 96, the passages being separated by partitions 97 tending to prevent the primary carburetors from interfering with one another. The passages 96 are of such size and so constructed and arranged as to maintain the same pressure in the primary carburetors as is maintained in the chamber 91a and passage 95 by the spring-loaded air valve 91; and permit part or substantially all of the primary air to pass from the air valve chamber 91a into the primary carburetors. For purposes of calibration it may be necessary to vary the size or shape of the passages 96 in order to get the proper fuel-air ratio at all speeds, as well as to vary the size or shape of the mixing chambers 41 and the angle of the junction of the passages 96 with the chambers 41. Such changes may be required according to the effect of velocity, inertia or restriction caused by changing the direction of the flow of primary air in conducting it from the air valve chamber 91a to the primary carburetors.

The mixing chambers 41 are connected by an equalizer provided by a horizontal passage 98 connected with vertical passages 99 for the purpose of equalizing the suction at the nozzles 43. This construction equalizes the pressure in the primary mixing chambers and tends to secure more equal distribution of the liquid fuel. Each passage 99 provides a vent for minimizing eddy currents above the fuel nozzles, which, if present, would upset uniformity of distribution of liquid to the mixing chambers 41. A baffle 100 is provided in this conduit to minimize eddy currents in passages 96. These eddy currents would tend to interfere with equal distribution of air to the mixing chambers 41 through the passages 96, and hence would upset the uniformity of distribution of the same fuel-air mixture to the various engine ports.

The passage of air into the air manifold is controlled manually by a butterfly throttle valve 101 supported by a throttle rod 102. The flow of primary fuel mixture from the primary carburetors is controlled by a single cylindrical valve member 103 having ports 104 each located in alignment with one of the mixing chamber passages 41. The control of the valves 101 and 103 will now be described:

Under conditions of relatively low speed and load, the air throttle 101 is kept closed and all of the fuel-mixture passes to the engine from the primary mixing chambers 41 through the primary tube 80, 81. For example, up to a vehicle speed of about 15 to 20 miles per hour, when the engine propels the vehicle on a level road, all of the fuel mixture may be supplied by the primary carburetors, the air valve 101 being closed. Due to the fact that the same depression is maintained in the air chamber 91a and the primary mixing chambers 41, the relation of the movement of

the valves 103 and 101 is not one that must be maintained with a great degree of accuracy.

The speed at which it is possible to operate the engine on fuel mixture supplied entirely by the primary carburetors, that is, without opening the air throttle 101, depends largely on the relative sizes of the tubes 80 and the air passages 96. In the carburetor herein disclosed these sizes are such that the engine may be run at speeds up to that represented by a vehicle speed of 20 to 25 miles per hour on a level, without opening the valve 101.

It has been found that the best operation can be obtained at idle by entirely closing the valve 101 and taking all of the mixture from the primary carburetors as indicated in Fig. 9. It is also possible however, to idle the engine and run at very low speeds with the air valve 101 slightly open, or to provide it with a small hole to admit additional air when idling.

Under all running conditions in which the air throttle 101 is open, a super-rich mixture is carried through the primary tubes 80, 81 to the secondary carburetors where the mixture is diluted by the air passing through the air manifold so as to provide the desired mixture for running under these conditions. By "super-rich" mixture is meant one which contains a greater amount of fuel than is properly combustible or desirable for steady running.

It may be here pointed out that the device herein disclosed differs materially from the earlier forms of the device in which separate throttles were employed at each secondary carburetor. In said earlier forms of device a "super-rich" mixture was formed in the primary carburetor at all times and under all operating conditions, because in such devices there was always a flow of air through the main air manifold under all operating conditions. To prevent the addition of such air making too lean a mixture for proper combustion the primary mixture necessarily had to be "super-rich".

In the present device better vaporization of the fuel in the primary carburetors and better distribution of such fuel is secured than in the earlier devices. Because of the passage of air through the main air manifold and the termination of the outlet tubes from the primary carburetors at points anterior to the several throttles in the earlier devices the air velocity in the primary tubes is low, and vaporization less effective than if a higher air velocity were maintained. Moreover, the low velocity air current in the primary tubes could not carry the fuel in suspension from the primary to secondary carburetors with as good results as could be obtained with a higher air velocity. Further, where the mixture is "super-rich" it is more difficult to vaporize the fuel or carry the fuel in suspension, and the greater the tend-

ency of the fuel to condense and collect on the walls.

In the device disclosed herein the primary tubes terminate posterior to the throttle where they are exposed to manifold suction under all operating conditions. The air velocity in such tubes is therefore high at all times securing superior vaporization and making the primary air current a better medium for carrying the fuel. Also since the mixture is "super-rich" only at higher motor speeds the difficulty of vaporization of such a mixture is not presented at all in the lower speed ranges, and since the velocity in the primary tubes increases at high speeds, the difficulty is largely negligible at any time.

The metering of fuel and air by the carburetor is not effected by the ratio of air passing the air throttle 101 to the air passing the primary valve 103, when the passages 96 and the mixing chambers 41 are so designed that the depression at the fuel nozzles 43 is maintained the same as the depression in the air chamber 91a, and when the construction is such that dynamic suction or velocity head does not affect the suction at these nozzles.

However, it has been found difficult, in practice, owing to frictional resistance, eddy currents and other factors to design a construction in which the effect of the dynamic suction or velocity head can be eliminated under all operating conditions and throughout all speed ranges, particularly at higher speeds. It is necessary therefore, that a definite relation be maintained between the opening movements of the valves 101 and 103, the valve 101 starting to open at a definite point in the opening movement of the valve 103, to prevent the mixture becoming too rich due to the effect of velocity on the jets, which effect would be apparent at some definite speed.

For instance in the present construction the pressures in the passage 95 and mixing chambers 41 remain substantially equal up to a vehicle speed of 20 to 25 miles an hour and the effect of velocity head does not appear. At higher speeds, because of the factors above referred to, the pressure in mixing chambers 41 becomes less than that in the passage 95 and the consequent velocity head becomes effective to produce increased fuel flow and consequent enrichment of the mixture. To compensate for this enrichment the valve 101 is opened to both reduce the velocity in the primary tubes and admit additional air to be added to the primary mixture in the secondary carburetor to restore the proportion of the mixture admitted to the engine. The proper running mixture is formed however at the secondary carburetors since the increase in volume of air passing through the air manifold is commensurate with the increase in richness of the primary mixture.

The coordination of the throttles 103 and 101 will now be described. The primary throttle 103 is provided with spindles 105 rotatably mounted in the wall of conduit 30 and to one of which is attached a lever 106 ⁷⁰ which may be controlled in the usual manner by an accelerator pedal or by a throttle lever located at the top of the steering column. The lever 106 carries a screw 107 for engaging a stop 108 to limit the closing movement of the throttle. The lever 106 is provided with a plurality of tapped holes 109 each for receiving a screw 110 providing a pivot for a link 111 having in its upper end a slot 112. The slot 112 receives a screw ⁷⁵ 113 attached to a lever 114 which is clamped to the shaft 102 of the air throttle 101. It is therefore apparent that a certain amount of clockwise motion of the lever 106 will take place as viewed in Fig. 6 before the ⁸⁰ shaft 102 will be rotated in this direction; or, as viewed in Fig. 9 a certain amount of counter-clockwise rotation of the valve 103 towards open position will take place before the valve 101 starts to open. The valve 101 ⁸⁵ is maintained closed by a spring 115 coiled around the shaft 102 having one end bearing against the stud 116 attached to the frame 30 and having its other end received by one of a plurality of holes 117 provided ⁹⁰ by a cam 118 also attached to the shaft 102. The spring is so biased that it tends to rotate the shaft 102 in a counter-clockwise direction as viewed in Fig. 6 in order to rotate the valve 101 in a clockwise direction as viewed in Fig. 9 the twisting effect of the spring can be varied by varying its connection with the cam 118.

When the engine is running idle, the air valve 91 will be nearly closed. Some of the ¹⁰⁵ air for idling will be admitted to the primary mixing chambers 41 through the passage 44 and the bushings 45. As the throttle 103 is opened to increase the speed of the engine, the valve 91 will be opened to admit ¹¹⁰ air to the primary carburetor. Up to 20-25 miles an hour at part-load, for example, the valve 101 will remain closed and all of the fuel mixture for the engine will be supplied preferably by the primary carburetor. ¹¹⁵ However the invention is not limited to the exclusion of additional air from the secondary carburetor. The air throttle 101 could be open a slight amount when the engine is idle, or it could be provided with a small hole through which a small amount of air could be supplied to the secondary carburetor during idling and under running conditions such as referred to. As the engine speed increases from zero with the opening of the ¹²⁰ throttle 103, the depression in the air chamber 91a will tend to increase, therefore the valve 91 will move further from its seat to allow more air to be admitted to the primary carburetor in order to maintain the proper ¹²⁵ 130.

fuel mixture proportions. After a certain speed has been reached, for example, about 20-25 miles per hour at part load, the air throttle 101 will be opened to permit more air to pass through the secondary carburetor in addition to that passing to it through the primary mixture tube 80. This prevents the engine mixture from becoming too rich for good performance and economy at higher speeds and under part load conditions as heretofore fully set forth.

When running with wide open throttle and the load is increased without change of throttle position, as when the vehicle on which the device is used ascends a hill, the depression in the air manifold and chamber 91a will decrease, permitting the spring 92 to move the valve 91 toward closed position. This will tend to reduce the supply of air admitted at the main air inlet and prevent a decrease in depression at the fuel jets, preventing a tendency to lean the fuel mixture, which would otherwise occur under such conditions of operation.

In order to provide for the metering of more liquid fuel to the primary carburetors under wide open throttle conditions to meet the condition of high speed or full load, means are provided for lifting the valve 64 shown in Fig. 14. This means includes a cam 120 (see Fig. 7) attached to one of the throttle spindles 105 and adapted to engage a lever 121 which is normally maintained by a spring 122 against a stop screw 123 attached to the block 31. The spring is connected with the lever 121 by screw 124 and with the block 31 by screw 125. The lever 121 is pivoted upon a screw 126 attached to the block 31. The lever 121 is provided with a notched ear 127 which receives a rod 128 provided at its lower end with the valve 64 (see Fig. 14). The upper end of the rod 128 is screwed into a nut 129. The underside of the ear 127 bears against a washer 130; and a spring 131 is located between the washer 130 and a collar 132 on the rod 128. The rod 128 extends through a hole 133 in the frame member 37. After the primary valve 103 has been opened a certain amount by the turning of the shaft 105 in a counter-clockwise direction as viewed in Fig. 7, the cam 120 will engage the lever 121 to cause it to move clockwise and to lift the rod 128 and to cause the valve 64 to open the port 63. As the primary throttle 103 is moved towards closed position, the spring 122 will return the lever 121 against the stop 123 and thereby cause the lever to push against the spring 131 and move the valve stem 128 downwardly to move the valve 64 into closed position.

When only the primary throttle 103 is open all of the liquid fuel is metered through the orifice 61 in order to keep the mixture lean for relatively low speed and load operation

or part throttle positions. For higher speed or greater load requiring the opening of the air throttle 101, it is desirable to meter more fuel into the passage 57. Therefore, the valve 64 may begin to lift as the valve 101 begins to open, or sometime after the opening movement of the said valve 101. The time of opening of the fuel valve 64 relative to the opening of valve 101 depends on the specific design of carburetor and the enrichment of the mixture caused by dynamic suction which may not be altogether eliminated. The valve 64 is not opened wide until the throttle is almost fully open. For example, the vehicle speed may be about 50 miles per hour when running on a level road before the valve 64 is entirely open.

The control of the air valve 91 for choking the carburetor will now be described. The housing 34 has an integral, inwardly extending arm 140 carrying a tubular extension 141 coaxial with the valve 91. A spring retainer sleeve 142 having a grooved collar 143, is vertically slidable upon the extension 141 and is provided with an annular groove 143 for receiving one end of the spring 92. The grooved collar 143 receives the studs 144 of a yoked lever 145 (see Figs. 4 and 9). Lever 145 is attached to a shaft 146 supported by the air port member 36, and has an arm 147 exterior to the member 36 provided with a hole 148 to which a carburetor choke rod 149 may be attached. Since the spring 92 tends to move the sleeve 142 downwardly, the lever arm 147 will be moved in a counter-clockwise direction as viewed in Fig. 3, into engagement with an adjustable stop screw 150 screwed into a hole in a clamp bracket 151 which may be tightened around the screw 150 in adjusted position by tightening a screw 152. Therefore by adjusting the screw 150 the compression of the spring 92 may be adjusted. To choke the carburetor when starting, the lever 147 is moved clockwise as viewed in Fig. 3, in order to move the sleeve 142 upwardly and compress the spring 92 beyond its normal state of compression. Since the air valve 91 is held closed, a greater depression will occur above the metering orifice 42 in each primary carburetor and an extra rich priming mixture will be drawn into the engine through the primary tubes 80. When the choke rod 149 is released the spring 92 will automatically return the lever 147 to its position against the stop screw 150.

Under accelerating conditions when suddenly opening the throttles, the transfer of fuel through the primary tubes 80, 81 to the engine tends to be less rapid than the passage of air through the air manifold, consequently the mixture tends to run lean until the richer mixture has had time to pass through the tubes 81, 80. This condition is aggravated by the fact that the manifold

suction decreases rapidly on the engine side of the throttle 101, while the air valve suction in chamber 91a and in the mixing passages 41 increases with the opening of the 5 throttle 101, thereby causing a decrease in the pressure differential between the ends of the primary mixture tubes. To prevent this temporary leaning of the mixtures, the sudden opening of the air valve 91 is retarded by 10 a dash pot to retard the flow of air to the engines, and an additional amount of fuel is added to the air which passes through the air manifold.

The control of the air valve 91 by the dash 15 pot will now be described. The valve 91 is attached to a rod 160 which passes through the tubular part 141 and through the tube 161 continuing from the lower end of the part 141 and attached to a partition plate 162 20 which is attached to the underside of the partition 94 by screws 163. The lower end of the rod 160 is attached to a piston rod 164 upon which a dash pot piston 165 is mounted for vertical sliding movement. A spring 166 25 which surrounds the rod 164 is maintained under compression between the piston 165 and a nut 167 attached to the rod 164. The spring urges the piston 165 against a flange 168 provided by the piston rod 164. The 30 piston 165 is provided with holes 169 communicating with an annular space 170 between the flanges 168 and the bottom of the piston 165 when the latter rests upon said flange. The flange 168 provides a seat for 35 a relief valve provided by the bottom of the piston 165. The flange 168 is provided with holes 171 which may be closed by the check valve disc 172 which is mounted for vertical sliding movement on an extension 173 of the 40 rod 164, the separation of the valve 172 from its seat provided by the flange 168 being limited by a washer 174 attached adjacent the bottom of the piston rod 164.

The piston 165 cooperates with a dash pot 45 cylinder 175 open at its upper end and closed at its lower end by a plug 176. The cylinder 175 is guided for vertical movement by tubular guide 177 integral with the frame part 37. The guide 177 is provided with an 50 opening 178 for permitting the passage of liquid fuel into the cylinder 175 through an opening 179. The opening 178 is made longer vertically than the opening 179 so that liquid fuel may enter the cylinder 175 55 in different positions thereof. The cylinder 175 is provided with a U-shaped pipe 180 providing a by-pass around the piston 165 in certain positions thereof (see Fig. 15). The inlet of the by-pass may be restricted if desired to control the rate of flow therethrough. Such a restriction is illustrated diagrammatically in Fig. 15. The pipe 180 is received by a vertical slot 181 in the guide 177 and therefore prevents rotation 60 of the cylinder 175 relative to the guide 65

177. Therefore, the holes 178 and 179 are always maintained in vertical alignment.

The cylinder 175 is provided with means for moving it vertically under certain conditions hereinafter more fully described, 70 such means comprising a groove 182 adjacent its upper end which receives studs 183 located on opposite sides of the cylinder 175 and projecting from arms 184 attached to a rod 185 supported by the frame member 37 75 and extending through the exterior thereof, where, as shown in Fig. 6, the rod 185 is attached to a lever 186. Lever 186 is provided with a series of holes 187 each for receiving a stud 188 extending from a block 189. The stud provides a pivotal connection 80 with the lever 186 and block 189 and is threaded at its end to receive a nut 190 in order to maintain the parts 186 and 189 assembled. The block 189 is provided with 85 an oblong opening 191 which receives a spring 192 and a washer 193 both surrounding a rod 194 which is guided at 195 and 196 by block 189. The washer 193 is pinned to the rod 194 so that the spring 192 tends 90 to urge the washer 193 against the wall 195 of the block 189 and to maintain the relation between the parts 189 and 194 as shown in Fig. 6. The upper end of the rod 194 is bent inwardly to engage a hole in the end 95 of a lever 197 which is pivoted upon a screw 198 attached to the block 30. The lever 197 is located in the path of movement of the cam 118 carried by the air throttle valve shaft 102. A spring 199 is coiled around 100 the screw 198 as shown in Fig. 8 and one end thereof bears against the block 30 and the other against the lever 197 in a manner such as to urge the lever 197 in a clockwise direction as viewed in Fig. 3. The spring 105 therefore tends to urge the lever 186 in the same direction and the cylinder 175 downwardly into its normal position as shown in Fig. 9. On opening movement of valve 101 the cam 118 acting through the medium of 110 lever 197, rod 194, and spring 192 operates to move the cylinder 175 upwardly when the spring pressure on lever 186 is greater than the fluid resistance to movement of the said cylinder. 115

If the primary throttle 103 be moved quickly from its idle position there will be a sudden depression in the air chamber 91a tending to cause the valve 91 to open quickly. The downward movement of the piston 165 is retarded by the liquid in the bottom of the cylinder 175 which cannot be moved relative to the piston 165 since the holes 171 in the flange 168 which provide the check valve seat will be closed by the check valve 120 disc 172. It is to be noted, however, that the piston 165 is retarded by the liquid in the cylinder 175 only during a certain portion of the downward movement of the piston. Referring to Fig. 15 it will be noted that the 125 130

piston 165 is normally located with respect to the by-pass 180 so that after the piston has moved about one-half of its permissible travel in the cylinder 175, the upper end of the by-pass 180 will be completely uncovered. Therefore, there is a relatively great resistance at the beginning of the downward movement of the air valve 91 and this resistance continues during only a small part of 5 the downward movement of the valve and then gradually falls off as the by-pass 180 is uncovered. This device, therefore, enables a sufficiently rich fuel mixture to be provided by the primary carburetor for the 10 purpose of accelerating the engine from low speed up to any speed.

If it is desired to accelerate from a low speed to a speed requiring at least the partial opening of the air throttle 101, means are 20 provided for adding more resistance to the opening of the air valve 91 such means being brought into operation by opening movement of said valve 101 in order that a richer than normal fuel mixture may be provided after the air valve 101 starts to open, 25 to provide fuel for acceleration from moderate to higher speeds. This means includes the mechanism operated by the cam 118 shown in Fig. 6. If the cam 118 is moved 30 slowly in a clockwise direction corresponding to a slow opening of the valve 101, the dash-pot cylinder 175 will be lifted relatively slowly and very little modification of the effect on air valve 91 by the dash-pot will 35 take place. But if the valve 101 be opened rapidly, the cam 118 will quickly force the lever 186 in a clockwise direction, and through the action of the spring 192 will move the cylinder 175 upwardly, while the 40 dash-pot 165 tends to move downwardly. This combined effect will tend to increase the pressure of the liquid between the bottom of the cylinder 175 and the piston 165, thereby tending to increase the retarding effect of 45 the dash-pot on the opening movement of the valve 91.

This operation will tend to increase the depression at the primary fuel nozzles so that the primary mixture will be temporarily 50 enriched.

The reason for employing a spring 192 for transmitting motion of lever 197 to cylinder 175 to move the latter upwardly is because of the inertia of the mass of the parts 55 which are connected with the lever 186. Too sudden downward movement of the lever 186 might cause undue strains on these parts, therefore, motion is applied gradually 60 through a spring. Moreover, the use of the spring permits a delayed lift in movement of the cylinder which permits the retarding effect on opening movement of the air valve to take place through a greater period of 65 time when the valve 101 is opened. This in-

sures the supply of a rich mixture throughout the entire acceleration period.

In addition to the above mentioned devices to provide necessary fuel for acceleration an injector pump is provided which is effective primarily at engine speeds above that at which valve 101 begins to open. When the valve 101 begins to open, although the opening of the main air valve is retarded some air flows past the main air valve, and through the main air passages, to the secondary carburetors. Although the retarding of the air valve opening will produce a sufficiently rich mixture in the primary carburetors to take care of acceleration, it takes 70 an appreciable time interval for such fuel mixture to pass to the engine ports. The inflow of air past valve 101 takes place immediately and unless some means were provided to prevent, this secondary air would 75 mix with whatever primary mixture did reach the secondary mixing chamber and momentarily weaken such mixture, so that the engine would not accelerate properly. To prevent this weakening of the mixture an 80 injector pump is provided, such pump being operated by the air valve in its opening movement to charge the secondary air referred to with fuel to form a mixture in the secondary mixing chamber sufficiently rich for acceleration purposes. As shown in Figs. 9 85 and 16, the cylinder 175 is provided within the fuel bowl 39 with an outlet pipe 200 connected with a valve seat member 201 closed by ball valve 202 held in closed position by 90 spring 203 which is caged within a fitting 204 attached to the valve seat 201. A pipe 205 attached to the fitting 204 extends to a point above the air inlet member 36 and then 95 downwardly at 206 into the air inlet 90 and 100 so bent as to direct a jet of fuel against the edge of the valve 91. The sudden movement of the throttle valves from any partially 105 open to nearly full open position will cause suddenly a relatively great depression in the 110 air chamber 91a and also a sudden lifting of the cylinder 175. Under these conditions the pressure of the liquid between the bottom of the cylinder and the piston 165 will be sufficient to lift the valve 202 from its seat 115 and to cause a quantity of liquid to be squirted from the pipe outlet 206 on the valve 91. This liquid fuel is broken up as it flies downwardly from the edge of the valve, and mixes 120 with the air passing to both primary and secondary carburetors.

While the above described pump can be operated to pump fuel wherever the air valve is opened by a depression sufficient to open the valve 202 and to overcome the effect 125 of leakage past the piston, such depression is not ordinarily communicated to the air valve on opening of the primary throttle alone but only after the valve 101 begins to open.

Under certain operating conditions where a great depression below the air valve is suddenly attained, it is desirable that the air valve open freely with no retardation. Under such conditions the pressure upon the liquid in the dash-pot may be great enough to overcome the spring 166, whereupon the piston will be lifted from the flange 168 of the piston rod to permit escape of liquid through the holes 169 in the bottom of the piston. As soon as the piston separates from the flange 168, it will remain separated until the pressure is relieved. This operation is known as the functioning of the blow-off valve.

The cylinder 175 is provided with the by-pass pipe 180 shown in Fig. 15 for the purpose of producing a variable retarding effect in accordance with the position of the piston 165 relative to the cylinder 175. As previously explained, while the engine is idling, the air valve 91 is opened but slightly because the depression in the chamber 91a is low. If the throttles are suddenly opened, the depression increases, and the valve 91 tends to open quickly but its motion is retarded by the dash-pot since the check valve 172 closes the holes 171 in the flange 168, requiring the liquid in the cylinder 175 all to leak around the piston 165. This damping effect persists relatively undiminished until the by-pass 180 begins to be uncovered by the piston, during which interval, a richer mixture will be supplied to the engine for purposes of acceleration. Then the damping gradually diminishes as the by-pass 180 is being uncovered to allow the valve 91 to open rapidly and supply air to the engine to give the required power. The relation of the by-pass to the piston and the restriction of the by-pass determines the duration of the valve-damping and this relation is varied automatically according to the position of the air throttle 101. The greater the initial opening of the air throttle 101 at the time it is suddenly opened further to accelerate, the less will be the damping action. This variation is present because less damping of the air valve would be required when moving from a 25 to a 35 mile-per-hour throttle position than from a 15 to a 35 mile-per-hour position, assuming that the grade of the road is substantially the same under both conditions. The position of the by-pass 180 relative to the piston 165 also determines the quantity of fuel pumped by the piston through tube 205.

As stated before, the sudden lifting of the dash-pot cylinder 175 has a momentary retarding effect upon the opening of the valve 91, because it tends to compress the liquid in the cylinder and to lift the piston with the lifting of the cylinder for a brief interval since the liquid does not have time to leak past the piston and permit the piston to move

downwardly relative to the cylinder. Therefore even though the piston were at the point of opening the by-pass, this momentary retarding of the air valve 91 might take place when the air throttle 101 was initially partly opened.

It is apparent from the foregoing description that the dash pot constitutes means for enriching the mixture only under part load conditions and on part throttle openings such as to produce low and intermediate vehicular speed. It is desired to accelerate to higher speeds, requiring a substantial opening of the air throttle 101, the rich mixture for acceleration is secured with the aid of the fuel injector. The reason for not being able to obtain the acceleration mixture under all conditions with the dash-pot alone is because when accelerating from a part throttle position of the air throttle 101 the by-pass 180 is practically uncovered by the piston 165; therefore the dash-pot would not retard sufficiently the further downward movement of the air valve 91 for purposes of enriching the mixture. One reason for the by-pass 180 can be explained by the following illustration. Suppose the vehicle is coasting at 40 miles per hour with the throttle closed, and the air valve 91 is nearly closed and then the throttles are suddenly to a position which will cause the vehicle to attain a speed of 50 miles per hour on the level. The air valve 91 must quickly move from the idle to the 40 mile-per-hour position. This position requires considerable relative downward movement of the piston 165 in the cylinder 175, and the piston should not be retarded unduly, as the engine being already up to speed, requires no addition of acceleration fuel. Hence the by-pass 180 is required. There may be some retarding of the air valve 91 before the by-pass is uncovered. If the pressure in the dash-pot is too great under these conditions the blow-off valve will relieve the pressure so that the valve 91 may more quickly move to the required position.

In Figs. 17 and 18 is disclosed a modified form of fuel valve which may be substituted for valve 70. This valve comprises an outer member 220, normally resting on seat 71. The member 220 is provided with an orifice 221, through which fuel flows when member 220 is seated. Rate of flow through said orifice is controlled by an inner valve member 222 movably mounted within member 220, movement thereof being controlled by a wire 223, forming a guide and stop to limit upward movement of member 222. The wire extends through a slot in member 222 and is secured in the walls of member 220. Member 222 is provided with a fuel feeding orifice of smaller diameter than orifice 221. In operation at very low speeds both members 220 and 222 are seated, and the orifice in member 222 controls the flow. As the speed increases

the member 222 is first unseated permitting flow around said member, the flow being controlled at this time by orifice 221. On still higher speeds the member 220 is lifted from its seat, permitting passage of fuel around as well as through such member.

- 5 In Figs. 19 and 20 is disclosed an alternative form of flow controlling member which may be used in place of the Venturi tube 85.
- 10 This member comprises an outer sleeve 230, received in a recess formed in the end of a manifold branch passage where the latter is attached to the engine block. At the opposite end of said sleeve an inwardly projecting
- 15 lip 231 is formed, said lip serving to collect any liquid deposited on the inner surface of such sleeve and direct same back into the stream of mixture flowing to the engine. Within the member a plurality of substantially straight cylindrical passageways are formed, through which the mixture flows. These straight passages cause the mixture to flow in straight paths, eliminating eddy currents and turbulence, thus causing some acceleration of flow. The passages may be formed by a plurality of separate cylinders secured within the sleeve or by a single sheet of metal bent in the form shown in Fig. 20. The primary tube 80 terminates at a point
- 20 adjacent the outer end of sleeve 231.
- 25 30 While the form of embodiment of the present invention constitutes a preferred form, it is to be understood that other forms might be adopted, all coming within the scope of the claims which follow.

What is claimed is as follows:

1. A charge forming device for internal combustion engines having in combination a plurality of secondary mixing chambers, a plurality of primary carburetors for supplying primary mixture to said secondary mixing chambers, a single throttle valve controlling flow of fuel mixture from the primary carburetors to the secondary mixing chambers and a single throttle controlling flow through the secondary mixing chambers.
- 40 45 50 55 60 65 70 75 80 85 90 95 100 105 110 115 120 125 130
2. A charge forming device for internal combustion engines having in combination a plurality of secondary mixing chambers, a plurality of primary carburetors for supplying primary mixture to said secondary mixing chambers, throttling means controlling flow of fuel mixture from the primary carburetors, throttling means controlling flow through the secondary carburetors and means for operating said throttling means concomitantly.
3. A charge forming device for internal combustion engines having in combination a plurality of secondary mixing chambers, a plurality of primary carburetors for supplying primary mixture to said secondary mixing chambers, throttling means controlling flow of fuel mixture from the primary carburetors, throttling means controlling flow

through the secondary carburetors and a common operating mechanism for said throttling means.

4. A charge forming device for internal combustion engines having in combination a plurality of secondary mixing chambers, a plurality of primary carburetors for supplying primary mixture to said secondary mixing chambers, throttling means controlling flow of fuel mixture from the primary carburetors, throttling means controlling flow through the secondary carburetors and a common operating mechanism for said throttling means said operating mechanism including means for operating one of said throttling means in advance of the other.

5. A charge forming device for internal combustion engines, having in combination a primary carburetor, a secondary carburetor, means admitting fuel and air to said primary carburetor to form a fuel mixture of properly combustible proportions, means conveying said mixture to the engine ports undiluted with additional air at all engine speeds below a certain predetermined speed, a primary throttle for controlling the flow of said primary mixture and a secondary throttle operated by said primary throttle for regulating the flow through the secondary carburetor and controlling the admission of additional air thereto.

6. A charge forming device for internal combustion engines, having in combination a primary carburetor, a secondary carburetor, means admitting fuel and air to said primary carburetor to form a fuel mixture of properly combustible proportions, means conveying said mixture to the engine ports undiluted with additional air at all engine speeds below a certain predetermined speed, a primary throttle controlling the flow of said primary mixture, and a secondary throttle operated on opening movement of said primary throttle when the latter is partly open, for regulating the flow through the secondary carburetor and the admission of air thereto.

7. A charge forming device for internal combustion engines having in combination a primary carburetor, air and fuel inlets therefor, a secondary carburetor, a passage connecting the primary and secondary carburetors, means for causing air to flow through said passage at high velocity to carry fuel from the primary to the secondary carburetor and means for effecting a flow of air past the fuel inlet at relatively low velocity to prevent the development of a velocity head at said fuel inlet.

8. A charge forming device for internal combustion engines having in combination a primary carburetor, air and fuel inlets therefor, a secondary carburetor, a passage connecting the primary and secondary carburetors, means for causing air to flow through said passage at high velocity to carry fuel

from the primary to the secondary carburetor and means for effecting a flow of air past the fuel inlet at relatively low velocity to prevent the development of a velocity head 5 at said fuel inlet, said last mentioned means comprising an air inlet in said passage between the outlet end thereof and the fuel inlet.

9. A charge forming device for an internal 10 combustion engine having in combination an intake passage therethrough, fuel and air inlets therefor, a valve controlling said air inlet, a dash-pot cylinder provided with means for admitting fuel thereto and a movable 15 piston connected to the air valve to control the movement thereof, means for moving the dash-pot cylinder to control the movement of the air valve, and a fuel conduit extending from the dash-pot cylinder to the 20 carburetor intake passage, said dash-pot acting to pump fuel through such conduit to the intake passage.

10. A charge forming device for an internal 25 combustion engine having in combination an intake passage therethrough, fuel and air inlets therefor, a throttle valve, a valve controlling said air inlet, a dash-pot cylinder provided with means for admitting fuel thereto and a movable piston connected to the 30 air valve to control the movement thereof, means operated by the throttle for moving the dash-pot cylinder to additionally control the air valve and a conduit for conducting fuel from the dash pot to the carburetor intake 35 passage on movement of the dash-pot piston or cylinder.

11. In a charge forming device for internal 40 combustion engines having a plurality of intake ports, an individual primary carburetor for supplying a fuel mixture to each intake port, a fuel supply chamber, a common duct for feeding fuel from said fuel chamber to all of said primary carburetors and a suction operated fuel valve in said fuel 45 feeding duct, said valve comprising two separately movable closure elements for differentially controlling the flow of fuel through the fuel feeding duct.

12. In a charge forming device for an internal 50 combustion engine having a plurality of intake ports, a main air manifold therefor having branches leading to said intake ports, a primary carburetor associated with each branch of said manifold, conduits connected with said primary carburetors and projecting into said branches of the main air manifold for conveying the primary mixture thereto, and straightener elements positioned in said branches adjacent the ends of 55 said conduits for causing the mixture passing through said branches to flow in straight paths.

13. A charge forming device for internal 60 combustion engines having in combination, a plurality of secondary mixing chambers, a

plurality of primary carburetors for supplying primary mixture to said secondary mixing chambers, primary throttling means associated with said primary carburetors, secondary throttling means cooperating with 70 said secondary mixing chambers and common operating mechanism for said primary and secondary throttling means comprising a lost motion connection.

14. A charge forming device for internal 75 combustion engines having in combination, a plurality of secondary mixing chambers, a plurality of primary carburetors for supplying primary mixture to said secondary mixing chambers, a single primary throttle controlling all of said primary carburetors, a single secondary throttle controlling the flow through all of said secondary mixing chambers, and means for operating the two throttles simultaneously. 80

15. A charge forming device for internal 85 combustion engines having in combination, a plurality of secondary mixing chambers, a plurality of primary carburetors for supplying primary mixture to said secondary mixing chambers, a single primary throttle controlling all of said primary carburetors, a single secondary throttle controlling the flow through all of said secondary mixing chambers, and common operating means for the 90 two throttles. 95

16. A charge forming device for internal 100 combustion engines having in combination, a plurality of secondary mixing chambers, a plurality of primary carburetors for supplying primary mixture to said secondary mixing chambers, a single primary throttle controlling all of said primary carburetors, a single secondary throttle controlling the flow through all of said secondary mixing chambers, and common operating means for the 105 two throttles comprising a lost motion connection.

17. A charge forming device for internal 110 combustion engines comprising a plurality of secondary mixing chambers, a plurality of primary carburetors for supplying primary mixture to said secondary mixing chambers, means admitting fuel and air thereto, a main air passage supplying air to said secondary mixing chambers, and means for equalizing the pressure in said primary carburetors comprising passages connecting said primary carburetors with each other and with the said main air passage. 115

18. A charge forming device for internal 120 combustion engines comprising a plurality of secondary mixing chambers, a plurality of primary carburetors for supplying primary mixture to said secondary mixing chambers, means admitting fuel and air thereto, a main air passage supplying air to said secondary mixing chambers, means for equalizing the pressure in said primary carburetors comprising passages connecting the primary car- 125

- buretors with the main air passage, and additional passages connecting the primary carburetors with the main air passage and adapted to reduce the velocity of flow through the primary carburetors.
19. A charge forming device for internal combustion engines comprising a plurality of secondary mixing chambers, a plurality of primary carburetors for supplying primary mixture to said secondary mixing chambers, means admitting fuel and air thereto, a main air passage supplying air to said secondary mixing chambers, pressure equalizing passages connecting the main air passage with the primary carburetors anterior to the fuel admitting means and additional passages connecting the main air passage with the primary carburetors anterior to the said equalizing passages to reduce the velocity of flow through the primary carburetors.
20. A charge forming device for internal combustion engines comprising a secondary mixing chamber, a primary carburetor supplying a primary mixture of fuel and air to said secondary mixing chamber, primary and secondary throttles controlling the primary carburetor and secondary mixing chamber respectively, a main air valve supplying air to the primary carburetor and secondary mixing chamber, a dash pot controlling the opening of the air valve and mechanism for simultaneously operating both the primary and secondary throttles and increasing the resistance of the dash pot to opening movement of the air valve.
21. A charge forming device for internal combustion engines comprising a secondary mixing chamber, a primary carburetor supplying a primary mixture of fuel and air to said secondary mixing chamber, primary and secondary throttles controlling the primary carburetor and secondary mixing chamber respectively, a suction operated air valve adapted to open as said throttles are opened, means for resisting the opening movement of said valve and means for simultaneously operating both said throttles and increasing the resistance of said resisting means to the opening movement of said air valve.
22. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors and a compound valve in said fuel feeding duct, said valve comprising two independently operable and telescopically arranged closure elements for differentially controlling the flow of fuel.
23. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors and a compound valve in said fuel feeding duct comprising two independently operable closure elements having passages formed therein to permit flow of fuel when said closure elements are seated.
24. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors and a compound valve in said fuel feeding duct comprising two independently operable closure elements having passages of different sizes formed therein, said closure elements being adapted to control the fuel flow successively.
25. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors, and a suction operated valve in said fuel feeding duct comprising two separately operable closure elements having passages therethrough and adapted to differentially control the flow of fuel through said duct.
26. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors, and a suction operated valve in said fuel feeding duct comprising two separately operable closure elements having passages of different sizes formed therein and adapted to be unseated successively as the suction increases, whereby the flow of fuel is progressively increased.
27. In a charge forming device for internal combustion engines having a plurality of intake ports, an individual primary carburetor for supplying a fuel mixture to each intake port, a fuel supply chamber, a common duct for feeding fuel from said fuel chamber to all of said primary carburetors, and a suction operated valve in said fuel feeding duct comprising two separately operable closure elements of different weights, the lighter of said elements having a relatively small fuel passage therein and the heavier of said elements having a larger passage therein, whereby the size of the fuel passage is progressively increased as the suction increases.
28. A charge forming device for internal combustion engines having in combination, an intake passage, fuel and air ports therefor, an automatic air valve controlling the air port, a throttle, means for enriching the mixture at low and high speeds comprising a dash pot

for resisting the opening movement of the air valve having a movable piston and movable cylinder, and an additional means for enriching the mixture at relatively high speeds.

5 29. A charge forming device for internal combustion engines having in combination, an intake passage, fuel and air ports therefor, an automatic air valve controlling the air port, a throttle, means for enriching the mixture at low and high speeds comprising a dash pot for resisting the opening movement of the air valve having a movable piston and movable cylinder, an additional means for enriching the mixture at high 10 speeds, and a fuel delivery conduit extending 15 from the dash pot to the intake passage.

30. A charge forming device for internal combustion engines having in combination an intake passage, fuel and air ports therefor, 20 an automatic air valve controlling the air port, a throttle, means for enriching the mixture at low and high speeds comprising a dash pot for resisting the opening movement of the air valve having a piston secured to 25 the air valve stem and a movable cylinder adapted to be moved by said throttle, and an additional means operable by the throttle for enriching the mixture at relatively high speeds.

30 31. A charge forming device for internal combustion engines comprising a mixing chamber, fuel and air inlets therefor, a fuel reservoir, a fuel duct connecting said reservoir with the fuel inlet, and a compound 35 valve in said fuel duct comprising two independently operable closure elements having passages formed therein to permit flow of fuel when said closure elements are seated.

32. A charge forming device for internal 40 combustion engines comprising a mixing chamber, fuel and air inlets therefor, a fuel reservoir, a fuel duct connecting said reservoir with the fuel inlet, and a suction operated valve in said fuel duct comprising two 45 separately operable closure elements having passages therethrough and adapted to differentially control the flow of fuel through said duct.

33. A charge forming device for internal 50 combustion engines comprising a mixing chamber, fuel and air inlets therefor, a fuel reservoir, a fuel duct connecting said reservoir with the fuel inlet, and a suction operated valve in said fuel duct comprising sep- 55 arately operable closure elements having pas- sages of different sizes formed therein and adapted to be unseated successively as the suction increases, whereby the flow of fuel is progressively increased.

60 In testimony whereof I hereto affix my signature.

WILFORD H. TEETER.
